[57] CLAIM

The ornamental design for a combined airplane assembly support member and control needle, as shown.

DESCRIPTION

FIG. 1 is a top plan view of a combined airplane assembly support member and control needle showing my new design;

FIG. 2 is a front elevational view thereof;

FIG. 3 is a right side elevational view, the left side being a mirror image thereof with the support member omitted;

FIG. 4 is a rear elevational view thereof; and

FIG. 5 is a bottom plan view thereof.

FIG. 4

FIG. 5
